US00D930428S

(12) **United States Design Patent** (10) **Patent No.:** **US D930,428 S**
(45) **Date of Patent:** **** Sep. 14, 2021**

(54) **BOTTLE**

(71) Applicant: **Sistema Plastics Limited**, Auckland (NZ)

(72) Inventor: **Cameron Lindsay**, Auckland (NZ)

(73) Assignee: **SISTEMA PLASTICS LIMITED**

(**) Term: **15 Years**

(21) Appl. No.: **29/684,845**

(22) Filed: **Mar. 25, 2019**

(30) **Foreign Application Priority Data**

Sep. 26, 2018 (NZ) 425019

(51) LOC (13) Cl. **07-01**

(52) U.S. Cl.

USPC **D7/392.1**; D7/396.2
